UNITED STATES PATENT OFFICE.

JOSEF PEJCHAR, OF BROOKLYN, NEW YORK.

DESIGN FOR A CUFF LINK.

Application filed September 3, 1926. Serial No. 18,965. Term of patent 14 years.

To all whom it may concern:

Be it known that I, Josef Pejchar, a citizen of the United States, and resident of the borough of Brooklyn, county of Kings, city and State of New York, have invented a new, original, and ornamental Design for a Cuff Link, of which the following is a specification, reference being had to the accompanying drawing, forming part thereof, in which—

Fig. 1 is a front elevation of a cuff link exhibiting my new design, and Fig. 2 is a side elevation thereof.

I claim:

The ornamental design for a cuff link, as shown.

JOSEF PEJCHAR.
